CHILDREN'S THEATER

William W. Collinger, William E. Hunn, and John W. Moore, St. Louis County, Mo., assignors to Cartoons Circus, Inc., St. Louis, Mo., a corporation of Delaware

Filed Jan. 12, 1962, Ser. No. 68,291

Term of patent 14 years

(Cl. D34—15)

FIG. 1

FIG. 2

FIG. 3

FIG. 4

The dominant features of our design reside in the portions shown in full lines.

We claim:

The ornamental design for a children's theater, substantially as shown and described.
